UNITED STATES PATENT OFFICE

108,007

DESIGN FOR A COMBINATION CLOCK AND WEATHER AND TEMPERATURE INDICATOR

Othneil G. Williams, Winsted, Conn., assignor to William L. Gilbert Clock Corporation, Winsted, Conn., a corporation of Connecticut

Application November 20, 1936, Serial No. 66,044

Term of patent 3½ years

To all whom it may concern:

Be it known that I, Othneil G. Williams, a citizen of the United States, residing at Winsted, in the county of Litchfield, State of Connecticut, have invented a new, original, and ornamental Design for a Combination Clock and Weather and Temperature Indicator, of which the following is a specification, reference being had to the accompanying drawing, forming a part thereof.

In the accompanying drawing:

Figure 1 is a front elevational view of a combi-

nation clock and weather and temperature indicator showing my new design; and

Figure 2 is a side view of my design.

The numerals appearing through the arcuate opening shown at the top of Figure 1 are merely representative.

I claim:

The ornamental design for a combination clock and weather and temperature indicator, as shown and described.

OTHNEIL G. WILLIAMS.
